UNITED STATES PATENT OFFICE.

GERALD W. HART, OF WEST HARTFORD, CONNECTICUT, ASSIGNOR TO THE HART MANUFACTURING COMPANY, OF HARTFORD, CONNECTICUT, A CORPORATION OF NEW JERSEY.

AUTOMATIC CIRCUIT-BREAKER.

No. 874,190.

Specification of Letters Patent.

Patented Dec. 17, 1907.

Application filed January 25, 1907. Serial No. 353,935.

To all whom it may concern:

Be it known that I, GERALD W. HART, a citizen of the United States, residing at West Hartford, Hartford county, Connecticut, have invented certain new and useful Improvements in Automatic Circuit-Breakers, of which the following is a full, clear, and exact description.

My invention relates to improved apparatus for use in connection with an electric circuit whereby a circuit may be broken automatically.

The invention is particularly useful in connection with lighting systems employed for illuminating various parts of a building. For example, assuming one of the chambers or rooms of a hotel is illuminated with electric lights; when the room is vacated the lights within the room will be extinguished by the mere locking of the door from the outside. It is undesirable that the unlocking of the door should close the circuit and turn on the lights, since many times the necessity for illumination, even when the door is unlocked and opened, is of no importance.

By this invention great economies are effected, since it makes it impossible for the user of a room to carelessly leave the same with the lights burning.

In the accompanying drawing; Figure 1 is a diagrammatic view showing my invention as applied to a lighting circuit. Fig. 2 is a view of certain details, in a different position from that indicated in Fig. 1. Fig. 3 is a diagrammatic view of a modification. Fig. 4 is a view of certain parts shown in Fig. 3 in a different position from that shown in said figure. Fig. 5 is a detail view, partly in section, of certain parts shown in Figs. 3 and 4.

In the form of my invention shown in Figs. 1 and 2 two switches are employed. Each of which switches are of the "three way" variety. I have also shown a solenoid in series with the lighting circuit. I have also shown an ordinary lock, such as found for example on a hotel room door. I have also shown means to coöperatively connect the lock with one of the switches. All of the parts are so arranged that when the circuit is closed and the door is shut and locked from the outside, the act of projecting the bolt will throw the switch, breaking the circuit and extinguishing the lights. This extin-

guishing of the lights by the breaking of the circuit also operates upon the switch actuating device in such manner as to throw it out of action until the circuit shall be again manually restored. As a result the act of unlocking and opening of the door will not close the circuit.

In the modification shown in Fig. 3 I have shown my invention as applied to a lighting circuit, in which there is only one switch, which switch may be both manually operated to turn on or extinguish the lights, and automatically operated (if the circuit is closed) to break the circuit when the door is closed and locked from the outside, as in the first instance.

While a broad principle is involved herein I will show the invention in only two of the many forms that it may take.

1 represents a door lock of any well known construction having a bolt 1^a operable from the outside.

2 represents a strike-plate having suitable cavities to receive the latch-bolt 1^b and dead-lock of the lock 1.

3 is a switch operating device which is supported and guided in any well known manner, the end of which may project into the cavity in the strike-plate 2 adapted to receive the bolt 1^a.

4 is a tilting latch-bar hinged on the operating device 3 and having a nose 4^a, which is arranged to engage (when the bolt 4 is elevated) one of the pins or projections 5—5 on a switch conventionally shown at 6.

7—7 are terminals which are electrically connected at all times. 8—9 are other terminals diametrically opposite the terminals 7—7, respectively.

10—11 are two terminals of a second switch while 12—12 are terminals opposite the terminals 10—11, respectively. The terminals 12—12 are electrically connected at all times.

14 represents conventionally a separate manually operable switch.

15 represents a solenoid.

15^a is a connection between the core of the solenoid 15 and the latch-bar 4.

16 is a spring exerting on bar 4 a depressing tendency in opposition to the lifting tendency of solenoid 15, when the latter is energized.

17 is a spring normally projecting the oper-

ating device 3 so that its end will stand approximately in the position shown in Fig. 1 when the door bolt 1^a is retracted.

The switch 6, the controller therefor, the 5 several springs and the solenoid may all be contained within a suitable casing 18 carried by the strike-plate 2 so that the same may be easily set up.

The electric circuit is substantially as follows: 19 is a positive or negative terminal wire, as the case may be, having therein a translating device such as a lamp 20. The wire 19 leads to and around the solenoid 15, from thence extends to the terminal 7—7. 10 The terminals 9—10 are electrically connected by the wire 21. Terminals 8—11 are connected by wire 22. The terminals 12—12 are connected to the positive or negative terminal wire 23. When the switches are in the 15 position indicated in Fig. 1, a circuit will be closed through the lamp 20 and solenoid 15 and both switches, with the result that the solenoid will be energized so as to lift the latch-bar 4 into a position where the nose 4^a 20 will engage the switch 6 ready for operation. The lock 1 stands opposite the strike-plate 2, indicating that the door is shut. 1^c is the usual dead-bolt which may be actuated by the usual well known thumb-turn 1^a, accessible only at the inner side of the door. If the occupant of the room unlocks the door by drawing bolt 1^c and leaves the room forgetting to extinguish the lights by operating the switch 14, the circuit will, nevertheless, be 25 broken and the lights extinguished the moment that he locks the door from the outside by projecting bolt 1^a since this act will force back the switch operating device 3 so as to turn the switch 6 through the medium of the 30 latch 4^a from the position indicated in Fig. 1 to that indicated in Fig. 2. This throwing of the switch not only breaks the circuit and extinguishes the lamp, but also deenergizes the solenoid 15, whereupon the latch-bar 4 35 will be drawn down under the influence of the spring 16, so that the nose 4^a will move out of the path of switch 6. The room then may be entered by the use of a suitable key by withdrawing the bolt 1^a, but this withdrawing the 40 bolt 1^a and the simultaneous projection of the operating device 3 under the influence of the spring 17, will not again restore the circuit, because, as will be seen, the switch engaging latch will then be in a position free of 45 the switch 6. When lights are required, however, the circuit may be closed by turning switch 14 so as to connect terminals 10—12, whereupon then the circuit will be closed through said terminals and terminals 50 9—7. This will simultaneously cause the light to glow and operate the solenoid 15, which will then draw the latch-bar 4 into position to again operate the switch 6 and break the circuit when the occupant of the 55 room again leaves and locks the door. The

apparatus illustrated in Figs. 1 and 2 contemplates the use of a supplemental automatically operable switch in addition to one for manual operation.

A further development of my invention 70 contemplates the use of a single switch, which may be both automatically, as well as manually operated. Such a modification is shown in Figs. 3 to 5, in which 2 is the strike-plate as before. 31 is the operating device 75 having (instead of the pivoted latch 4) the pivoted or yielding end 41. The spring 161 provides a pressure on one side of said extension 41, while the spring 171 exerts pressure in a direction to project the head 31 outwardly in the bolt opening in the strike-plate. 61 represents conventionally the switch. This switch may have any suitable form of handle for manually controlling the same. 61^a represents conventionally the 80 shank of such handle or thumb-turn. This switch 61 may have pins 51—51 corresponding to pins 5 in Fig. 1. These pins are diametrically placed alternately with other pins 51^a. As shown, there are two other pins 90 51^a—51^a having outwardly hooked or offset ends for the purpose hereinafter described. 41^a is a hook on the lower side of the extension 41. The extension 41 normally rests upon the pins 51—51^a. When the head 31 95 is projected and the parts are as shown in Fig. 3, the switch will be in position to close the circuit through terminals 71—81. In this figure the extension 41 lies in such position that the hook or nose 41^a is ready to 100 engage one of the pins 51 as soon as the operating device 31 is pushed in. When the door is shut and the door bolt projected this pushing in of the operating device 31 occurs, whereupon the switch 61 will be swung in the 105 position shown in Fig. 4, and the circuit will be broken. In this position it will be noted that the offset end of one of the pins 51^a is bearing under a yielding member 25, carried by the extension 41 springing it upwards. 110 When the door bolt is withdrawn and the head 31 is projected forward under the influence of the spring 171, the extension 41 will be drawn forward with it, freeing the hook 41^a from the pin 51. When this occurs, the member 25 will exert a sufficient lifting tendency upon the bar 41 to tilt it up so that the hook 41^a may be reciprocated above and free of the switch and thus it will have no effect upon the latter. It follows, 120 therefore, that the circuit can only be closed by a manual act as in the first instance. This manual act may be effected by the usual thumb-turn connected with the switch at 61^a and accessible at the inside of the room. 125 The mechanism shown in Figs. 3 to 5, inclusive, requires no solenoid, but the purpose or function thereof is accomplished in effect mechanically in the manner above described. The distance that this switch 61 is from the 130

head 31 is immaterial, since that is variable by the length of the connection back of the head 31. Of course, if desired, the switch and associated parts shown in Fig. 3 may be housed within one casing as shown in Fig. 1, but this is not essential, nor is it, in fact, essential in Fig. 1.

What I claim is:

1. In an electric circuit, manually operable means for closing said circuit, in combination with a door-lock bolt operated means for opening said circuit, only, and means for disconnecting said door bolt from the circuit operating means when the circuit is open.

15 2. In an electric circuit, a hand-operated controlling switch, in combination with a secondary switch operated by a door bolt and acting only to open said circuit after the same has been previously closed by means of 20 said hand-operated switch, and means to operatively disconnect said bolt from said secondary switch at other times.

3. The combination with the wires forming an electric circuit of two circuit controlling means, one of said means being hand-operated for closing and opening said circuit, the other of said means operating only to open said circuit after the same has been manually closed, means to hold the latter operating means out of operative relation to the circuit at all other times.

4. In a circuit controlling system, the combination with the wires for forming an electric circuit of a hand-operated switch, a door bolt operated switch, and means whereby the operation of the door bolt operated switch becomes effective only when the circuit is closed.

5. In a circuit controlling system, the combination with the wires for forming a circuit of two-circuit controllers in series, and means whereby one of said circuit controllers becomes effective only when the circuit is closed.

45 6. The combination with translating device in a chamber of a circuit for supplying electrical energy to said translating device, a hand-operable circuit controller for energizing or deenergizing said translating device, a door, a bolt for said door; a secondary circuit controller operable by said bolt, and means whereby the operation of the secondary controller is effective only when the cir-

cuit has been previously closed by said hand operable controller.

7. In a device of the character described, a circuit, two switches therein, a bolt, and means for coöperatively connecting the bolt with one of said switches to operate the latter to break the circuit when said bolt is moved in one direction, the movement of said bolt in an opposite direction leaving said switch unaffected.

8. In a device of the character described, a circuit, switch mechanism therein, a bolt, and means for coöperatively connecting said bolt with said switch mechanism to operate the latter to break the circuit when said bolt is moved in one direction, the movement of said bolt in an opposite direction leaving said switch mechanism unaffected, said connecting means comprising an operating part arranged to be directly engaged by said bolt, a latch carried thereby for directly engaging the switch mechanism when the circuit is on; but being free of said switch mechanism when the circuit is open.

9. In a device of the character described, a circuit, switch mechanism therein, a bolt, and means for coöperatively connecting said bolt with said switch mechanism to operate the latter to break the circuit when said bolt is moved in one direction, the movement of said bolt in an opposite direction leaving said switch mechanism unaffected, said connecting means comprising an operating part arranged to be directly engaged by said bolt, a latch carried thereby for directly engaging the switch mechanism when the circuit is on but being free of said switch mechanism when the circuit is open, and a solenoid for controlling said latch.

10. An automatic circuit breaker for use in connection with a door-lock comprising switch mechanism for the circuit, an operating device arranged to be operated by the bolt of a door lock, means for connecting the said operating device with said switch mechanism when the circuit is closed and means for freeing said operating device from said switch mechanism when said circuit is open.
